IRONING STAND

Thomas S. Zastrow, St. Paul, Minn., assignor to
General Mills, Inc., a corporation of Delaware

Application May 2, 1949, Serial No. 90,895

10 Claims. (Cl. 248—117.3)

1

This invention relates to ironing stands and more particularly to a simplified form of insulated stand.

Numerous constructions have been proposed in the past for the support of an ordinary flatiron or steam iron when the iron is not in use. Many of these stands include a layer of insulating material to prevent undesired transfer of heat from the iron to the table or other support on which the stand is placed. Many of these insulated stands are complicated and expensive to manufacture.

It is accordingly one object of the present invention to provide a simplified construction for an ironing stand.

A further object is the provision of a stand in which a metal supporting plate and a layer of heat-insulating material are combined in an improved manner.

Still another object is an ironing stand in which a supporting plate and a heat insulating layer are firmly interconnected without the use of rivets, screws, or bolts.

Other objects and advantages of the invention will be apparent from the following specification in which a preferred form of ironing stand has been described.

In the drawings which form a part of this specification,

Figure 1 is a perspective view of an ironing stand incorporating the improvements of the present invention.

Fig. 2 is a sectional view on the line 2—2 of Fig. 1, but with the insulating material removed for clarity, and

Fig. 3 is a sectional view on the line 3—3 of Fig. 1.

The ironing stand according to the present invention includes a supporting plate 10 which is preferably metallic. Supporting plate 10 has a downwardly extending peripheral flange 12 provided with spaced supporting projections 14 for engagement with a table or other surface on which the stand is to be located. Flange 12 and the spaced projections 14 support the plate 10 a predetermined distance above the table and thus permit circulation of air beneath the plate. The relatively narrow contact areas on the projections 14 also reduce to a minimum the possibility of heat transfer from the plate to the table or support.

In accordance with the invention, a portion of heat insulating material is mounted on the plate so that the insulating material lies above the plate or projects above it. Thus an iron which

2

is placed on the stand will be supported by the insulating material rather than directly by the metallic plate 10. The insulated support serves a twofold purpose in that the relatively soft material of the insulating layer prevents damage to the soleplate of the iron by scratching, and at the same time prevents direct transfer of heat from the iron soleplate to the supporting plate 10 of the stand.

10 The stand of the present invention is particularly designed for use with a steam iron or steam ironing attachment. For this purpose, the insulating material has been selectively located on the supporting plate 10 of the stand at relatively 15 small areas which are spaced from each other. Thus when the steam ironing device is placed on the stand, it will be held slightly above the supporting plate 10 by the spaced areas of insulating material so that the discharge of steam from the iron may be continued without blocking the usual steam outlets of the iron by the insulating areas and thereby condensing large quantities of moisture within the insulating material.

15 In the form of device shown in Fig. 1, the insulating material is arranged in two rows which are spaced from each other and substantially parallel to each other. The particular form of insulating material which is preferred is a woven tubular strip of asbestos fiber. Two such strips designated as 16 and 18 are mounted in spaced rows on plate 10 as described.

20 In order to lock the insulating strip 16 readily, the supporting plate 10 is provided with a row of at least two spaced openings such as the openings 20 and 22 in the drawings. Intermediate openings 24 and 26 may be provided, if desired, these openings being separated by an integral retaining strip 28 beneath which the strip of insulating material 16 may be laced.

25 A substantial portion 29 of insulating strip 16 extends across the top of supporting plate 10 adjacent the opening 20, i. e., in this case between openings 20 and 24. A similar portion 30 of the insulating strip 16 likewise extends across the top of the supporting plate adjacent the opening 22 and extending toward the opening 26. The free ends 31 and 32 of insulating strip 16 thus extend downwardly through the openings 20 and 22 respectively to the region beneath the supporting plate 10.

30 The second and spaced strip of insulation 18 is similarly positioned with respect to corresponding openings 33, 34, 35, and 36 in the supporting plate. A strip 38 between openings 35 and 36 holds the central portion of strip 18 in position,

just as in the case of strip 28 in connection with insulating member 16.

With respect to insulating strip 16, the inner edges of openings 20 and 22 are provided with downwardly projecting flanges 40 and 42, respectively, around which the free ends 31 and 32 of the insulating material are doubled back beneath the plate. Projections 40 and 42 assist in preventing accidental withdrawal of the free ends of the strip through the openings 20 and 22. Similar lips and flanges 44 may be provided at the outer edges of openings 20 and 22 and also at the outer edges of openings 24 and 26 to provide a relatively smooth finish at these points.

According to the invention suitable clamping means are provided on the supporting plate 10 for engagement with the free ends 31 and 32 of the insulating strip 16 to clamp the free ends against the bottom of the supporting plate. As shown in Figs. 2 and 3, the clamping means for free end 31 include one or more integral lugs struck downwardly from the area of plate 10 which lies beneath the portion 29 of insulating strip 16. In this case two such lugs 46 and 48 are provided. The opening 50 which is left in plate 10 by downward bending of the lug portions 46 and 48 has opposite edges 52 and 54 to which the lugs are integrally attached. Edges 52 and 54 are spaced apart a distance corresponding substantially to the width of portion 29 of the insulating strip so that opening 50 extends transversely beneath strip 16 for substantially the full width of the strip. Thus the lugs 46 and 48, which are initially deformed vertically downward as in the heavy line position of Fig. 2, are spaced apart a distance sufficient to accommodate the width of the free end 31. Free end 31 is accordingly doubled back against the bottom of plate 10 between the lugs 46 and 48, after which the lugs are deformed to the dotted line position of Fig. 2 to clamp the free end 31 firmly in position.

Similar lugs 56 are struck downwardly to form another opening 58 which lies beneath the area of portion 33 of the insulating strip. Lugs 56 engage and clamp the doubled back free end 32 in position as shown in Fig. 3. In this figure, the free end 31 has been left unclamped while free end 32 is clamped in order to show the relative steps in assembly of the stand.

As indicated in Fig. 3, the clamping lugs 56 deform a portion 60 of free end 32 upwardly into the opening 58. This upward deformation of free end portion 60, in combination with the doubling back of the free end around projecting lip 42, provides a strong and effective retaining means which prevents accidental withdrawal or slippage of the insulating strip out of opening 22. The remaining free ends of the respective strips 16 and 18 are, of course, clamped in position in like manner.

According to the foregoing description, a construction has been provided in which a flexible insulating strip is readily attached to a supporting plate 10 to form an ironing stand which has a minimum of parts, which can be made by simple stamping and bending operations, and in which firm attachment of the insulating material is achieved without the use of unsightly screws or rivets which might also mar the surface of the iron to be placed on the stand.

Since minor variations and changes in the exact details of construction will be apparent to persons skilled in this field, it is intended that this invention shall cover all such changes and

modifications as fall within the spirit and scope of the attached claims.

Now, therefore, I claim:

1. An ironing stand comprising a horizontal supporting plate having an opening therein, a combination supporting and heat-insulating member having an iron-supporting portion extending across a substantial area of the upper surface of the plate adjacent the opening with a free end extending down through the opening and lying substantially parallel to and against the undersurface of the plate adjacent the opening, and an integral portion of the plate adjacent the opening being bent downwardly from the plane of the plate and engaging and clamping the free end of the member against the under surface of the plate, the clamping engagement of said free end by said integral portion of the plate constituting the sole securing means for the insulating member at said free end.

2. An ironing stand comprising a horizontal metal supporting plate having at least two spaced openings therein, a combination supporting and heat-insulating member having an iron-supporting portion extending across the upper surface of the plate between the openings with a free end extending down through each opening, and an integral lug struck downwardly from the plane of the plate adjacent at least one opening and engaging and clamping the corresponding free end of the member against the bottom of the plate, the clamping engagement of said corresponding free end by said integral lug constituting the sole securing means for the insulating member at said corresponding free end.

3. An ironing stand according to claim 2 in which the integral lug is located beneath the portion of the insulating member extending across the top of the plate.

4. An ironing stand comprising a horizontal metal supporting plate having an opening therein, an insulating member having a portion extending across the top of the plate adjacent the opening with a free end extending down through the opening and doubled back against the bottom of the plate beneath said portion, and clamping means on the plate located beneath said portion and engaging said free end.

5. An ironing stand according to claim 4 in which the clamping means comprises at least one integral lug struck from an area of the plate located beneath said portion and substantially concealed by said portion.

6. An ironing stand comprising a horizontal metal supporting plate having separate rows of at least two spaced openings each, an insulating strip at each row, each strip having a portion extending across the top of the plate between the spaced openings with its free ends passing down through the openings and doubled back against the bottom of the plate beneath said portion, and integral clamping means on the plate beneath said portion engaging and holding said free ends.

7. A stand according to claim 6 in which the clamping means includes at least one integral lug struck from an area of the plate located beneath said portion and substantially concealed by said portion.

8. An ironing stand comprising a horizontal metal supporting plate having an opening therein, a flexible insulating strip having a portion extending across the top of the plate adjacent the opening with a free end passing down

through the opening and doubled back against the bottom of the plate beneath said portion, and a pair of lugs struck from an area of the plate beneath said portion to form a second opening, the free end lying between said lugs and being engaged and partially deformed into the second opening by the lugs.

9. An ironing stand according to claim 8 in which the plate includes a downwardly projecting lip at the edge of the first mentioned opening, said free end being doubled back around the lip, and said lugs being located substantially adjacent the lips.

10. An ironing stand comprising a horizontal metal supporting plate having an opening therein, a flexible insulating strip having a portion extending across the top of the plate adjacent the opening with a free end passing down through the opening and doubled back against the bottom of the plate beneath said portion, and a pair of 20

5 lugs struck from an area of the plate beneath said portion to form a second opening, the lugs being integrally connected to the plate at opposite edges of the second opening which are substantially parallel to the strip portion and spaced transversely corresponding to the width of said strip portion, the free end lying between said lugs and being engaged and partially deformed into the second opening by the lugs.
